S. MENYHERT & V. SMITH.
GRINDING IMPLEMENT.
APPLICATION FILED NOV. 4, 1913.

1,089,247.

Patented Mar. 3, 1914.

UNITED STATES PATENT OFFICE.

STEPHEN MENYHÉRT AND VENDEL SMITH, OF NEW BRUNSWICK, NEW JERSEY.

GRINDING IMPLEMENT.

1,089,247.

Specification of Letters Patent.

Patented Mar. 3, 1914.

Application filed November 4, 1913. Serial No. 799,234.

To all whom it may concern:

Be it known that we, (1) STEPHEN MENYHÉRT and (2) VENDEL SMITH, (1) a subject of the King of Hungary and (2) a citizen of the United States, and residing at New Brunswick, in the county of Middlesex and State of New Jersey, have invented certain new and useful Improvements in Grinding Implements, of which the following is a specification.

This invention relates to grinding implements.

The object of the invention is to provide a simple and thoroughly efficient article of the above character, which shall preferably be hand driven, and in the use of which not only flat surfaces may effectively be ground, but mechanically accurate bevels may be imparted to knives, plane-bits, chisels, and the like.

With the above and other objects in view, as will appear as the nature of the invention is better understood, the same consists in the novel construction and arrangement of parts 25 of a grinding implement as will be herein-after fully described and claimed.

In the accompanying drawing, forming part of this specification and in which like characters of reference indicate corresponding parts: Figure 1 is a view in side elevation of a grinding implement constructed in accordance with the present invention. Fig. 2 is a vertical longitudinal sectional view through the implement. Fig. 3 is a 35 fragmentary detail sectional view showing a part of one of the grinding wheels employed with the implement.

Referring to the drawings, 1 designates the base of the implement, having combined, 40 preferably integral therewith, two standards 2 and 3 having suitable journals formed therein in which is mounted a shaft 4. This shaft extends at both ends beyond the standards and has keyed to it at one terminal 45 a bevel gear 5, and at its other end an abrading or grinding wheel 6 which may be of metal coated with an abradant or may be wholly of an abradant as may be preferred.

Mounted on the shaft between the standards is an abrading wheel 7 which may be constructed in the same manner as the wheel 6 and is preferably hollow, and has one edge 8 beveled to coöperate with a similarly beveled edge 9 formed on an abrading wheel 10 also mounted upon the shaft, the two

wheels being held combined by screws 11, of which two are herein shown, the heads of the screws being countersunk in or bearing upon the head 12 of the wheel 7, while the outer ends of the screws are threaded into the wheel 10. The head 12 of the wheel 7 is provided with a socket 13, and the wheel 10 with a similar socket 14, and these two sockets are designed to receive a coiled spring 15 surrounding the shaft and bearing at its ends against the walls of the socket. The function of this spring is to cause the two wheels to separate, as shown in Fig. 3, when the screws 11 are loosened, so as to increase the size of the beveled groove or channel formed between the two wheels by the inclined faces 8 and 9. To permit access to the screws 11 for the purpose above described, the head 16 of the wheel 7 is provided with two openings 17 that are disposed in alinement with the screw heads and through which a screw driver may be inserted. Below the inclines 8 and 9, is formed a diamond-shaped channel or groove 18 formed by oppositely beveling the opposed faces of the wheels 7 and 8, and this groove is designed to permit the edge of an implement being sharpened, say of a knife, of being inserted any desired distance between the two wheels without contacting, at its edge, with the metal thereof.

The means for driving the shaft 4 comprises a relatively large gear wheel 19 which is carried by a stub shaft 20 mounted in an obliquely-disposed bearing 21 carried by the upper end of the standard 3, the oblique disposition of the wheel 19 permitting free application of a tool of any character to the entire surface of the wheel 7.

In order to permit the wheel 7 to have a sliding movement on the shaft 4, and yet positively turn therewith, a key 22 is provided which is seated in a key-way in the shaft and engages a similar key-way in the head 16, the key-way being of sufficient length to permit the desired longitudinal adjustment of the wheel 7.

From the foregoing description, it will be seen that the implement of this invention, while simple in character, will be found thoroughly efficient for the purposes designed, and may be readily mounted upon a table or the like and used for house-hold purposes.

What is claimed as new and desired to be secured by Letters Patent of the United States is:—

1. An implement of the class described comprising two grinding wheels, one of which is longitudinally adjustable relative to the other, the opposed faces of the wheels being beveled in opposite directions adjacent to their edges, and also oppositely beveled to provide a channel concentric with the peripheries of said wheels.

2. An implement of the class described comprising two grinding wheels, the opposing faces of which are beveled in opposite directions, one of said wheels being hollow and formed with openings, a spring interposed between the wheels, and screws alined

with said openings for adjusting one of the wheels relative to the other.

3. An implement of the class described comprising a grinding wheel having one edge beveled, a second wheel adjustable to and from the first and having also a beveled edge, each of said wheels being oppositely beveled near its periphery to provide a channel, and means for adjusting one wheel relative to the other. 25

In testimony whereof we affix our signatures in presence of two witnesses.

STEPHEN MENYHÉRT.
VENDEL SMITH.
